UNITED STATES PATENT OFFICE.

EDOUARD WIELAND, OF BIEL-MADRETSCH, SWITZERLAND.

SEWING MACHINE FOR DARNING.

Application filed February 4, 1927. Serial No. 165,793.

The subject-matter of this invention is a sewing machine comprising an improved device for repairing knitted goods, e. g. hose, and the like.

5 In knitting devices used heretofore for this purpose so-called tongue needles penetrate the work and draw the working thread from the other side of the work through the latter forming the loops or stitches.

10 In contradistinction thereto, in the machine according to the present invention the working thread is brought, similarly as in a sewing machine, by an eyeleted needle through the work into the reach of a gripper and a stitch needle.

15 By means of this mode of operation which is the opposite of the former method the following important advantages are obtained:—

20 1. The perforating needle can be so selected for each piece of work to be performed that it can pass to and fro through practically every kind of fabric or knitted material, however fine the mesh or stitches, without any danger of tearing loop or stitches at the edge of the hole to be knitted.

25 2. As the working thread never leaves the hole of the feed needle which has no movable tongue or latch, no knots and consequently no disturbance in working can occur during the feed of the thread, as is the case in machines having tongue or latch needles.

30 3. The last row of stitches can be finished on the machine, which in known machines must be done by hand after removal of the work.

35 4. The breadth of the patch can be varied according to the shape of the hole in the work for saving thread, whilst in known machines the breadth must be made and maintained from first to last corresponding to the maximum breadth of the hole.

40 5. The edges of the damaged part of the work are not strained by tongue or latch needles penetrating the fabric.

45 In the machine according to the present invention the sewing needle, when knitting, serves as knitting needle and as thread feeder which is intended to bring the working thread for forming loops and stitches through the stretched work and for bringing through within reach of the sewing machine gripper a loop that is held on the

55 other side of the work by a loop holder in the path of the knitting needle and transversely thereof. Between a frame carrying the work and the loop holder is situated a row of sinker or loop needles moved individually to and fro in succession, which needles take up in order to the loop or stitches formed by the gripper and deliver them to the loop holder before the formation of a new loop or stitch.

60 According to another feature of the invention, the gripper is formed as a double-ended swinging gripper which can form stitches or loops in both directions of swinging as it has two oppositely directed gripping points.

65 Further, according to the invention there is provided a device by which the entire row of loop needles can be so shifted step-by-step transversely to the loop needles that these needles are brought in succession within reach of a positively controlled slide that serves for withdrawing the loop needle situated in the path of the knitting needle for the delivery of the stitch or loop held by it and for clearing the path of the knitting needle, and also serves for feeding it forward, for receiving the new stitch or loop, in the same row of the other loop needles.

70 75 80 85 Other features of the invention will be described hereinafter and pointed out in the claims.

90 The invention is illustrated diagrammatically and by way of example in the accompanying drawings wherein like reference characters designate like parts throughout the several views, and in which

95 Figure 1 is a side elevation, partly in longitudinal section through the lower part of a machine according to the invention,

Figure 2 is a plan showing half of the front part of the machine base-plate,

Figure 3 is a plan of the lower part of the machine below the base-plate,

Figure 4 is a cross-section, enlarged, taken on the line IV—IV in Figure 1, and

Figure 5 is a cross-section, enlarged, taken on the line V—V in Figure 1;

Figure 6 shows the material transporter, as seen from the front, enlarged, when used for sewing, and

Figure 7 is a plan of the same;

Figures 8 and 9 are two views of the

switch device for the row of loop needles, as seen in the direction of the arrow VIII shown in Figure 1;

Figures 10 and 11 show the change-over device for the drive of the switch device as seen from the front, according to the arrow X shown in Figure 1, and

Figure 11^a is a detail view of parts shown in Fig. 11;

Figures 12 to 21 illustrate the operation of the machine when knitting in different stages;

Figure 22 is an elevation of the drive of the material transporter, and

Figure 23 is a detail view of parts of the same;

Figures 24 and 25 show a sinker needle in plan and side elevation, respectively, on an enlarged scale;

Figures 26, 27 and 28 are cross-sections thereof, and

Figure 29 is a plan of the loop opener.

According to the drawings, the base-plate 1 of the sewing machine is provided at its rear end in the usual manner with a hollow upper arm 2 which contains, likewise in known manner, a driving shaft 3 and driving mechanism for a needle rod 4 and a thread feeder 5. These parts are only partly shown and may be formed in any convenient manner.

At the underside of the base-plate 1 is arranged a trough-shaped casing 6 having in its bottom a broad groove 7 wherein a slide 8 is slidable lengthwise of the machine. This slide can be fixed in its end positions by any convenient means, not illustrated. For using the machine for sewing the slide is fixed in its rear position shown by broken line in Figure 1; in the front position shown in full lines in Figure 1, the slide is placed ready for using the machine for knitting. In order conveniently to shift the slide 8 from one end position into the other a pivot 9 depends from the slide through a longitudinal slot 10 in the bottom of the casing 6 and through a lever 11 which is rotatable about a pivot 12 and can be grasped by a hand at its free end.

A gripper shaft 15 is journaled in an upwardly extending arm 13 fixed on the bottom of the casing 6 and in a cross-bar 14 fixed at both ends in the latter. This shaft carries at its rear end a pinion 16 that meshes with a considerably larger toothed wheel 17 carried by a horizontal axle 18 rotatable on the pedestal of the upper arm 2. On the rear face of the gear wheel 17 is arranged a link 19, into which extends a pin 20 of a connecting rod 21 pivoted in the usual manner to a crank, not shown, of the driving shaft 3. The pivot pin extends also into a slide block 22 of a link 23 which is mounted to rock at about the middle of its length about a pivot 25 rotatable in the rear

wall 24 of the casing 6. This link 23 is locked in one of the slanting positions shown in Figures 10 and 11 by one or other of two pawls 26 and 26¹, whichever engages in the lower end of the link 23. During the upward and downward movement of the connecting rod 21 the pivot 20 slides, according to the position of the link 23, on one or other side of the vertical plane passing through the pivots 18 and 25, as the pivot 25 is situated below the pivot 18 and the block 22 moves only in the upper half of the link 23. According to the position which this link occupies, therefore, the pin 20 drives the wheel 17 on one side or the other. The gear ratio of the two wheels 16 and 17 is so selected that when the wheel 17 rotates 90° the wheel 16 rotates about 250°.

The front end of the shaft 15 carries a double gripper having two gripper points 27¹ spaced apart and directed towards one another, between which the sewing or knitting needle 28 of the needle rod 4 extends when the gripper is in the position shown in Figures 4 and 16. The two gripper points enable the gripper to form loops or stitches when swinging in either direction out of the starting position shown in Figures 4 and 16. The gripper 27 serves, when sewing, like an ordinary ring gripper for receiving the lower thread-spool 29 and for forming loops, but works, when sewing, in only one direction, whilst when knitting it works in both directions alternately for forming rows of loops. When not in use, i. e. when knitting, the annular shuttle 29 lies on an annular holder 30 which is mounted to swing up and down at 32 on the bottom of the casing 6 by means of an arm 31, and is held both in its vertical and in its lowered position by a bent, laterally resilient arm 33.

Immediately behind the gripper there is fast on the shaft 15 a cam disc 34 which serves for lifting the material transporter 35 (Figs 1, 3, 6 and 7). In Figure 1 this transporter is not shown because the sewing machine is used for knitting in the position in which it is shown. This transporter 35 is at the free end of a lever 36 pivoted to a lever 37 whose shaft 38 is driven by a device described hereinafter. When not in use the transporter 35 lies swung away to one side as shown in Figure 3 and in broken lines in Figure 6.

The shaft 38 lies parallel to the shaft 15 and carries fast on its rear end, away from the lever 37, a lever 39 to which a swinging member 40 (Fig. 22) is pivoted. This member 40 is mounted on a pivot 41 of a slide block 42 slidable in a link 44 able to rock about a pivot 43 carried in the pedestal of the upper arm 2. The upper end of this swinging member 40 is forked at 45 and em-

braces a cam disc 46 fast on the main shaft 3. When the cam 46 rotates, the member 40 is rocked to and fro about the pivot 47 on the lever 39 and the block 42 is thereby reciprocated in the link 44. As the latter is placed slantwise the swinging member 40 is simultaneously moved up and down, this movement being more or less according to the position of the link 44. The shaft 38 is thereby oscillated, by which the levers 37 and 36 are reciprocated with the transporter 35 which during one of its longitudinal movements is lifted by the cam 34 into the operative position indicated in broken lines in Figure 6.

A hollow shaft 48 is slidable lengthwise on the shaft 15, and is provided at its front end with a control disc 49, to whose front face a cam 51 is attached by means of a screw 50. In the front end position of the hollow shaft this cam 51 is detachably coupled with the shaft 15 by a pin 15¹ that is arranged on the shaft 15 and enters into a recess 51¹ of the disc open at the front. The disc 49 has at its rear side a cam groove 52, in which runs an anti-friction roller 53 (Fig. 4) mounted on an arm 54 of a yoke 55. This yoke of U-shape is mounted to swing laterally about a pivot 56 fast on an eye 57 of the slide 8. At the upper end of the yoke 55 are two bolts or studs 58, one in each limb, which bolts together carry at their front ends a flat bow 59 having in the middle two spaced, rearwardly directed, oppositely bent hooks 60 serving as loop opener (Figs. 19, 18 and 29). Outside the hooks 60 two fingers 61 extend rearwardly and prevent the loop from being opened too wide by the gripper.

Two rearwardly extending, upwardly bent levers 63 (Fig. 3) are journaled coaxially in the side walls of the slide 8, each on a pivot 62. A cross-bar 63¹ connecting these levers together carries in the middle an antifriction roller 65 on a rearwardly directed arm 64 extending slantingly upwards; this roller 65 is pressed against the periphery of the cam 51 by the action of a spring 66 pressing upwards one of the levers 63 which are thus controlled by the cam. The levers 63 carry at their upper ends a cross-bar 67 (Figs. 4 and 13) connecting them together and having in the middle two upwardly and forwardly extending points 68 which together constitute a loop holder. The distance between these points of the loop holder is so great that the needle 28 can readily pass between them. The cross-bar 67 is provided between these points with a recess 69 permitting the needle to pass through it. The points serve for withdrawing a loop 70 from the loop or sinker needle 71 above them and for holding open the loop in reach of the needle 28 when this descends for forming a new loop.

Sinker needles 71 (Fig. 3) are situated below a cover plate 72 in a broad groove 73 of a slide 74 movable transversely of the shaft 15. These needles lie close one beside another and are formed at their front ends, 70 which generally extend forwardly to the cover 72, as shown in Figures 24 to 28 inclusive. The point of each sinker needle is formed by a long tongue 71¹ considerably thinner and less high than the stem 71². In order to facilitate the loop-holder points 68 passing through a loop on the sinker needle, the latter is provided at the top of its point with two lateral lugs or flanges 71³, 75 so that the needle point is of T-section at 80 that part, as shown in Figure 26. A thread embracing the needle at this place therefore leaves, as indicated in broken lines in Figure 26, below the flanges sufficient space for the entry of the points 68 into the loop. The sinker needle 71 which is situated just under the knitting needle 28 is drawn back, when the latter descends, by the device described hereinafter so that it disappears completely 85 with its point under the plate 72, and the latter removes from its point the loop 70 on the needle in question (Fig. 15).

The shaft of each sinker needle is provided at its rear free end on its lower side with a recess 75. Into the recess of the 95 sinker needles situated beside the needle 28 there extends, from below, a cross-bar 76 (Fig. 1) fastened to the side walls of the slide 8, by which bar all the sinker needles are held against forward and backward 100 movement. There engages in the recess 75 of the sinker needle situated below the needle 28 a nose 77 of a rod 78 which is guided to move lengthwise under the sinker needle in question in a corresponding recess 79 of 105 the cross bar 76 and in the rear end wall 8' of the slide 8. The rod 78 is engaged by means of a downwardly extending roller 80 with a cam groove 81 of a control drum 82 at the rear end of the hollow shaft 48, by 110 which drum the rod 78 and the sinker needle 71 coupled with it is retracted and pushed forward with each swing of the shaft 48.

In order that at each swing of this shaft 48 a different sinker needle may be actuated, the slide 74 which is guided in suitable recesses in the side walls of the slide 8, is shifted with all the sinker needles a step equal in length to the thickness of the latter. For this purpose the slide 74 is provided on 120 its underside with a toothed rack 83 with which a pinion 84 meshes (Figs. 1 and 3). This pinion is fast on a shaft 85 journaled parallel to the shaft 15 in bearings 86 on the one side wall of the slide 8 and in the arm 13 on the bottom of the casing. The shaft 85 carries beside the pinion 84 a ratchet wheel 87, in which engages a detent 88 which is bevelled on both sides and is carried by a spring 89 secured on the slide 8, whereby the 125 130

shaft 85 and with it the slide 74 is held in a given position. The two wheels 84 and 88 extend into a recess 90 of the adjacent side wall of the slide 8, so that when the latter is shifted the shaft 85 moves with it.

At its rear end the shaft 85 carries close together two ratchet wheels 91 and 92 (Figs. 8 and 9) having oppositely directed teeth. In the working position of the slide 8 these wheels 91, 92 are situated within reach of two pawls 95 and 96 rotatable about two pivots 93 and 94 on the gear wheel 17, each of which pawls is held under the influence of a spring 97 bearing against a pin 98 and lies in the general plane of its allotted ratchet wheel. According to the position of the link 23 and consequently according to the working direction of the link 19 the pawl 95 temporarily engages with the ratchet wheel 91 or the pawl 96 with the ratchet wheel 92. The shaft 85 is rotated by the pawl 91 in one direction and by the pawl 92 in the opposite direction and consequently the slide 74 is fed one step in the corresponding direction in each case. In order automatically to change the direction of feed the following device is provided.

Two arms 99 (Fig. 5) extend from the slide 74 to the rear beyond the sinker needles 71. At the rear ends these arms 99 carry a rod 100 that is parallel with the slide 74 and has fine toothing on its underside. On the rod 100 are two stops 101 and 102 which are pressed upwards by leaf springs 103 (Fig. 5) housed in them so that teeth 104 formed on their lower parts mesh with the toothing of the rod 100 and are thereby held at the desired position, and extend upwards through a slot 1' in the base plate 1. When the stops 101 and 102 are depressed against the action of their springs 103 they can be shifted along the part of the rod 100 carrying them and be adjusted as desired. A two-armed lever 105 free to rotate about the hollow shaft 48, the two ends of which lever are forked, extends from below the stops 101 and 102 into their reach. The lower end of this lever 105 embraces a pin 106 which extends rearwardly from a lever 107 of a shaft 108, so that the lever 105 can slide on the pin to the rear without leaving it. The shaft 108 is journaled on the one hand in the rear wall 8' of the slide 8 and on the other hand in the rear wall 84 of the casing 6. On the rear end of the shaft 108 is fast an upwardly extending arm 109 and behind this are pivoted the two pawls 26 and 26' aforesaid. These pawls are provided each with an executive lug or extension 112 and 113, to each of which is attached from below a tension spring 114, so that the pawls always bear against stops 115 extending from the wall 24, by which their upward movement is limited. In this position the free ends of the pawls 26 and 26' are within reach of the

lower end of the link 23 whose end positions are limited by stops 116 on the wall 24. At both sides of the arm 109 connecting rods 117 and 118 are pivoted to the pawls 26 and 26', which rods have their upper ends connected by links 119 with the arm 109.

If the lever 109, whose end positions are limited by a stop pin 111 extending through a slot 110 in the lever, is rocked by the shaft 108 out of its end position indicated in broken lines in Fig. 10 into the end position shown in full lines, which occurs at the moment when the block 22 is in its upper end position, the rod 117 is brought by its link 119 into the reach of a projection 120 of the block 22 that lies out of the general plane of the lever 109. This block 22 has on its opposite side a similar horn-like projection 120' for the rod 118. When the block 22 descends and its horn 120 strikes the rod 117, the pawl 26 is moved by the latter down out of the link 23. Shortly afterwards the block 22 hits against the upper end of the arm 109 with a shoulder 120'' arranged on the horn 120. A torque is now exerted to the left on the block by the arm 109 and as the pivot pin 20 of the block has arrived in alignment with the pivot 25 of the link 23, and the latter is thus relieved from any force acting on it, the link 23 swings from the position shown in Fig. 10 into that according to Fig. 11. In this position the link is arrested by the pawl 26. The changed position of the link 23 then occasions the rocking of the link 19 of the wheel 17 to the opposite side so that the pawl 96 then begins to coact with the ratchet wheel 92 which turns the shaft 85 intermittently in the opposite sense and thereby shifts the slide 74 with the sinker needles to the opposite side.

In order that when the slide 8 shifts the hollow shaft 48 may also be moved the latter is provided in a head 121 with an annular groove 122, into which there engages from below a fork 123 fast on an arm 8' of the slide 8 (Figs. 1 and 5).

A downwardly curved frame 124 serves for holding the work, which frame is surrounded by an elastic tie, for example an endless coil spring, 125, which lies in a groove 126 in the frame and tightly stretches on the latter a piece of work drawn down over it. The frame 124 is so suspended by means of two arms 127 that it can swing forwards and backwards on two curved standards 128 mounted detachably in the slide 74. These standards extend upwards through an aperture 129 in the plate 1 and are removed from the slide 74 when the machine is to be used for sewing. After the removal of the standards or posts 128 from the slide 74 the rear part of the aperture 129 can be closed by a flap 130 which is hinged at 131 to the plate 1 and is folded back to the rear during knitting, as shown in Fig. 1. The front end

of the aperture 129, which affords access to the gripper and shuttle, can be closed as usual by a sliding shutter 132.

The manipulation and operation of the described machine for knitting may be briefly described as follows:—

The slide 8 is first set in its front end position. After turning back the flap 130 the standards 128 are placed into the slide 10 74 and the frame 124 provided with the work is hung on the standards. The shuttle holder 30 is set in its inclined position, so that the shuttle 29 is removed from the gripper 27 and lies in the holder 30.

15 The transporter 35 is swung outwards as shown in Fig. 3. By rotating the main shaft 3 the thread feeder 5 and the needle rod 4 are actuated in the usual manner. The connecting rod 21 turns the toothed 20 wheel 17 to and fro in the manner described above, whereby the shafts 15 and 48 are rotated to and fro corresponding to the gear ratio of the wheels 16 and 17 out of the 25 position shown in Figs. 16 and 17 into the position according to Figs. 20 and 21 and reversely, or in the opposite direction a like amount according to the position of the link 23. When the cam 82 rotates, the rod 78 retracts the sinker needle 71 coupled with 30 it behind the cover plate 72 shortly before the needle 28, which is descending at the same time, arrives at the height of the sinker needle. As the sinker needle recedes the loop holder 67, 68 moves forward. The 35 loop holder does not assist in forming the first row of loops. The needle 28 descends into the gripper 27 (Figs. 16 and 17) which makes the thread in the usual manner (as when sewing) in the form of a loop which, 40 during its formation, is held open by the rearwardly swung hooked bow 59, 60. When the sewing needle ascends and the loop is drawn upwards the latter is hung on the simultaneously advancing sinker 45 needle. At the moment when the needle 28 and the pivot 30 have reached their upper end positions the shaft 85 and with it the slide 74 is fed one step by one of the pawls 95 and 96, whereupon the cycle of operations for forming another loop can begin 50 afresh.

Assuming that the first row of loops or any subsequent one has been made the operation of forming a stitch is as follows:—

55 When the needle 28 descends and the sinker needle recedes the loop of thread hanging on the latter is swept off by the cover plate 72 and as soon as it is situated on the flanges 71''' is seized by the forwardly moving loop holder 68 (Figs. 14 and 15) and is so brought into the path of the needle 28 that this, after piercing the work, enters through the loop into the gripper 26 (Figs. 16 and 17). In the lowest position of the needle 60 65 28 the loop holder 68 recedes and releases

the old stitch. The gripper 27 then seizes below the latter the thread of the needle 28 and forms the loop for the new stitch (Figs. 18 and 19). Before this loop is released by the gripper the sinker needle 71 passes 70 through it (Figs. 20 and 21). After the release of the loop it is pulled tight by the thread feeder until it lies on the sinker needle. In the upper end position of the needle 28 the shaft 85 is fed one step with 75 the slide 74 and the entire row of sinker needles, whereupon a new stitch is formed in the manner described above.

The stops 101 and 102 are set on the rod 100 according to the breadth of the row 80 of stitches to be formed. As soon as one of these stops hits the lever 105 (see stop 102 in Fig. 5) the lever 109 is reversed by the lever 105, pivot 106, lever 107 and shaft 108. The link 23 is then rocked from one 85 end position into the other in the above described manner at the next descent of the block 22 by the rod 117 or 118, whereupon the slide 74 with the sinker-needles is fed in the opposite direction. The movement 90 of the work frame from one row of stitches to the next before a new row begins is brought about by the action of a spring or weight not illustrated. The last row of 95 stitches is simply knitted or, if desired, sewn to the work.

The use of the machine for sewing will be readily understood. The posts 128 with the frame 124 are removed from the slide 74. The slide 8 is shifted into its rear end 100 position indicated in broken lines in Fig. 1 together with the members used for knitting connected with it. The shafts 48 and 85 are thereby moved endwise. The shaft 48 is disconnected from the pin 15' so that, 105 during sewing, the gripper shaft 15 which is not movable endwise, can alone rotate. When the shaft 85 moves backwards the ratchet wheels 91 and 92 move out of the reach of the pawls 95 and 96. Then the 110 work transporter 35, 36 is swung inwards into its working position. The aperture 129 is closed by the cover 130 and shuffer 132 after the spool holder 30, 31 with the spool 29 has been swung up. After the 115 other operations usual for sewing have been performed, the machine can be used for sewing.

While a preferred construction of machine has been described above in detail it 120 is to be understood that I do not limit myself to the constructional details enumerated, but

I claim:—

1. In a sewing machine, a knitting device 125 comprising in combination a sewing needle serving as knitting needle and thread feeder, a frame for the work, a loop holder said needle being arranged to bring the thread for forming loops and stitches through the 130

- comprising in combination a sewing needle serving as knitting needle and thread feeder, a frame for the work, a loop holder situated in the path of the needle, and a sewing-machine gripper having two points, which needle is adapted to bring the thread for forming loops and stitches through work on the frame and through a loop held on the other side of the latter by said loop holder into the reach of said gripper, a gripper-shaft carrying the latter and adapted to swing its points in the path of the thread, a row of sinker or loop needles between said frame and said loop holder and adapted to receive loops from the gripper, a device for shifting the entire row of sinker needles stepwise transversely of the direction of their length, means for reciprocating the sinker needle situated in the path of the sewing needle for delivering the previously formed loop to the loop holder and for taking up the new loop formed by the gripper, means for reversing the direction of traverse of the sinker needles, a hollow shaft surrounding the gripper shaft, a cam on the hollow shaft, a lever that is controlled by said cam and carries said loop holder, a second cam on the hollow shaft, a rod that is controlled by said second cam and is so connected with the sinker needle in the path of the sewing needle as to reciprocate the same, means for holding all the other sinker needles with their ends all in a line and against endwise movement, a slide carrying said sinker needles one beside another, and posts detachably carried by said slide, from which posts said frame, which is curved downwardly, is pivotally suspended.
6. In a sewing machine, a knitting device comprising in combination a sewing needle serving as a knitting needle and thread feeder, a frame for the work, a loopholder situated in the path of the needle, a sewing-machine gripper having two points, which needle is adapted to bring the thread for forming loops and stitches through the work on the frame and through a loop held on the other side of the latter by said loop holder into the reach of said gripper, a gripper-shaft carrying the latter and adapted to swing its points in the path of the thread, a row of sinker or loop needles between said frame and said loop holder and adapted to receive loops from the gripper, means for reciprocating the sinker needle situated in the path of the sewing needle for delivering the previously formed loop to the loop holder and for taking up the new loop formed by the gripper, a hollow shaft surrounding the gripper shaft, a cam on the hollow shaft, a lever that is controlled by said cam and carries said loop holder, a second cam on the hollow shaft, a rod that is controlled by said second cam and is so connected with the sinker needle in the path of the sewing needle as to reciprocate the same, means for holding all the other sinker needles with their ends all in a line against endwise movement, a slide carrying said sinker needles one beside another, means comprising a rack-and-pinion and pawl-and-ratchet mechanism operated by said gripper shaft and adapted to shift said slide and sinker needles stepwise transversely of the direction of length of the needles in both directions, a rod that is parallel with and firmly connected to said slide, two stops adjustable on said rod, a lever free to rotate about said hollow shaft and extending between said stops, which latter lever is adapted to operate a reversing device for a link that serves to guide a slide block of a second link which is fast on a driving wheel that meshes with a pinion fast on the gripper shaft, which driving wheel carries two pawls of said pawl-and-ratchet mechanism.
8. In a sewing machine, a knitting device comprising in combination a sewing needle serving as a knitting needle and thread feeder, a frame for the work, a loop holder situated in the path of the needle, a sewing-
- nected with the sinker needle in the path of the sewing needle as to reciprocate the same, means for holding all the other sinker needles with their ends all in a line and against endwise movement, a slide carrying said sinker needles one beside another, and means comprising a rack and pinion and pawl-and-ratchet mechanism operated by said gripper shaft and adapted to shift said slide and sinker needles stepwise transversely of the direction of length of the needles in both directions.
7. In a sewing machine, a knitting device comprising in combination a sewing needle serving as a knitting needle and thread feeder, a frame for the work, a loop holder situated in the path of the needle, a sewing-machine gripper having two points, which needle is adapted to bring thread for forming loops and stitches through the work on the frame and through a loop held on the other side of the latter by said loop holder into the reach of said gripper, a gripper-shaft carrying the latter and adapted to swing its points in the path of the thread, a row of sinker or loop needles between said frame and said loop holder and adapted to receive loops from the gripper, means for reciprocating the sinker needle situated in the path of the sewing needle for delivering the previously formed loop to the loop holder and for taking up the new loop formed by the gripper, a hollow shaft surrounding the gripper shaft, a cam on the hollow shaft, a lever that is controlled by said cam and carries said loop holder, a second cam on the hollow shaft, a rod that is controlled by said second cam and is so connected with the sinker needle in the path of the sewing needle as to reciprocate the same, means for holding all the other sinker needles with their ends all in a line against endwise movement, a slide carrying said sinker needles one beside another, means comprising a rack-and-pinion and pawl-and-ratchet mechanism operated by said gripper shaft and adapted to shift said slide and sinker needles stepwise transversely of the direction of length of the needles in both directions, a rod that is parallel with and firmly connected to said slide, two stops adjustable on said rod, a lever free to rotate about said hollow shaft and extending between said stops, which latter lever is adapted to operate a reversing device for a link that serves to guide a slide block of a second link which is fast on a driving wheel that meshes with a pinion fast on the gripper shaft, which driving wheel carries two pawls of said pawl-and-ratchet mechanism.
10. In a sewing machine, a knitting device comprising in combination a sewing needle serving as a knitting needle and thread feeder, a frame for the work, a loop holder situated in the path of the needle, a sewing-machine gripper having two points, which needle is adapted to bring the thread for forming loops and stitches through work on the frame and through a loop held on the other side of the latter by said loop holder into the reach of said gripper, a gripper-shaft carrying the latter and adapted to swing its points in the path of the thread, a row of sinker or loop needles between said frame and said loop holder and adapted to receive loops from the gripper, means for reciprocating the sinker needle situated in the path of the sewing needle for delivering the previously formed loop to the loop holder and for taking up the new loop formed by the gripper, a hollow shaft surrounding the gripper shaft, a cam on the hollow shaft, a lever that is controlled by said cam and carries said loop holder, a second cam on the hollow shaft, a rod that is controlled by said second cam and is so connected with the sinker needle in the path of the sewing needle as to reciprocate the same, means for holding all the other sinker needles with their ends all in a line against endwise movement, a slide carrying said sinker needles one beside another, means comprising a rack-and-pinion and pawl-and-ratchet mechanism operated by said gripper shaft and adapted to shift said slide and sinker needles stepwise transversely of the direction of length of the needles in both directions, a rod that is parallel with and firmly connected to said slide, two stops adjustable on said rod, a lever free to rotate about said hollow shaft and extending between said stops, which latter lever is adapted to operate a reversing device for a link that serves to guide a slide block of a second link which is fast on a driving wheel that meshes with a pinion fast on the gripper shaft, which driving wheel carries two pawls of said pawl-and-ratchet mechanism.

machine gripper having two points, which needle is adapted to bring thread for forming loops and stitches through work on the frame and through a loop held on the other 5 side of the latter by said loop holder into the reach of said gripper, a gripper shaft carrying the latter and adapted to swing its points in the path of the thread, a row of sinker or loop needles between said frame 10 and said loop holder and adapted to receive loops from the gripper, means for reciprocating the sinker needle situated in the path of the sewing needle for delivering the previously formed loop to the loop holder 15 and for taking up the new loop formed by the gripper, a hollow shaft surrounding the gripper-shaft, a cam on the hollow shaft, a lever that is controlled by said cam and carries said loop holder, a second cam on said 20 hollow shaft, a rod that is controlled by said second cam and it so connected with the sinker needle in the path of the sewing needle as to reciprocate the same, means for holding all the other sinker needles with 25 their ends all in a line against endwise movement, a slide carrying said sinker needles one beside another, a second slide that is mov-

able parallel with said gripper-shaft carries the first said slide that is movable intermittently transversely thereof, which second 30 slide is coupled with said hollow shaft that is longitudinally movable on the gripper-shaft so that when the second slide is shifted the hollow shaft moves with it and is disengaged from the gripper-shaft. 35

9. In a sewing machine having a knitting device, a gripper-shaft a gripper carried thereby and a slide movable on said shaft, said knitting device being for the most part arranged on said slide, a material transporter, a member carrying said material transporter; a rocking shaft adjacent said slide, a lever on said rocking shaft for moving said member to and fro and adapted to be swung outwards, a cam behind said gripper, on which cam the said member bears and is adapted to lift the said member from time to time with said material-transporter into the working position relative to said knitting device. 40 45 50

Signed at Berne, Switzerland, this 22d day of January, 1927.

EDOUARD WIELAND.
